ATTORNEY

John B. Smith
WITNESS

UNITED STATES PATENT OFFICE.

GEORGE SMITH, OF PHILADELPHIA, PENNSYLVANIA.

TOBACCO PIPE.

Application filed March 31, 1922. Serial No. 548,396.

To all whom it may concern:

Be it known that I, GEORGE SMITH, a citizen of the United States, residing at Philadelphia, in the county of Philadelphia and 5 State of Pennsylvania, have invented new and useful Improvements in Tobacco Pipes, of which the following is a specification.

This invention relates to tobacco pipes, and it has for its primary object to provide 10 a novel structure of pipes for the use of tobacco smokers which is fitted with a trap in the stem intermediate the bowl and the mouthpiece of the pipe and in communication therewith, said trap serving to collect 15 the saliva and nicotine in the drawing of the smoke from the bowl to the mouthpiece proper.

A further object of this invention is to provide a separable stem adjacent a trapped 20 pipe of the foregoing character which allows for the cleaning of the saliva and nicotine from the said trap.

A further object of my invention is to provide a pipe of the foregoing character, the 25 stem portion thereof being separable, the co-operating ends of said separable portions of the stem being cup-shaped and provided with partitions which constitute a trapped chamber in the passage-way through the 30 stem; said partitions nearest the pipe bowl having a perforation in its lower portion to allow for the saliva and nicotine to drain into the trap. The other of said partitions having a perforation in its upper portion 35 for the passage therethrough of the smoke. I also provide a by-pass on the upper portion of the stem, said by-pass communicating with the trap and the passage-way in the bowl stem to facilitate the drawing of dry smoke from said passage-way through the 40 by-pass into the trap and thence through the other partition into the mouthpiece.

A further object of the invention resides in the fact that the above referred to by-pass serves as a lock member and while it 45 has been specified as a by-pass it may obviously be a solid member and serve only as a locking device as between the separable portions of the pipe stem trap.

In the further disclosure of the invention reference is to be had to the accompanying 50 sheet of drawings constituting a part of this specification and in which like characters of reference designate the same or corresponding parts in all the views.

Figure 1— is a vertical longitudinal view partly in section showing one practical embodiment of my novel form of tobacco pipe.

Figure 2— is a sectional elevation taken on the line 2—2 in the preceding figure; and, 60

Figure 3— is a similar transverse section taken substantially on the line 3—3 in Figure 1.

Referring more particularly to the views the same showing a preferred embodiment 65 of my novel tobacco pipe, the numeral 1 designates the bowl of the pipe which is in communication with a separable stem 2, said stem being provided at its outermost portion with a mouthpiece 3. The stem 2 is made 70 separable and consists of the portion 4 which is integral or otherwise attached to the bowl 1 of the pipe and the intermediate portion 5 onto which is screw-threaded the mouthpiece stem 6 which is fashioned at its outer end 75 with the above referred to mouth-hole or piece 3. The portion 4 of the pipe stem is enlarged and hollowed out to provide a cup-shaped end 7 which is internally screw-threaded at 8. The cup-shaped portion 7 is 80 in communication with the bowl 1 of the pipe through the passage-way 9. In this cup-shaped end 7 there is removably positioned a partition 10 having in its lower portion a perforation 11, the function of which 85 will be more fully explained hereinafter.

The intermediate portion 5 of the stem is cup-shaped as at 12 and externally screw-threaded at 13 for co-operative connection into the aforesaid internally screw-threaded 90 part 8 of the pipe stem 4 to hold said parts together to form a unitary stem. In the cup-shaped portion 12 there is also removably positioned a partition 14 having a perforation 15 at its upper part, the function 95 of which will be later on explained. The partitions 10 and 14 in the cup-shaped members 7 and 12 provide for the three separate compartments 16, 17, 18, the compartments 16, 17 communicating with each other 100 through the by-pass or duct 19, on the upper portion of the stem.

The outer end of the intermediate portion 5 is reduced and provided with a passage-way 20 which communicates with the compartment 18 and the passage-way 21 in the mouthpiece portion 6, said mouthpiece portion being appropriately screw-threaded into the intermediate portion 5 as shown. 105

The compartment 17 constitutes a trap to 110

hold the saliva and nicotine in the smoking of the pipe, the operation of the parts 4 and 5 allowing for the cleansing of said compartment or trap 17.

5 In the smoking of my novel tobacco pipe the trap 17 provides a means for arresting the nicotine and saliva and prevent the same from being drawn with dry smoke into the smoker's mouth. The by-pass 19 allows 10 for the passage of perfectly dry smoke therethrough into the upper portion of the trap and from thence into the mouthpiece 6. The arrangement of the trap 17 and the compartments 16, 18 in the enlarged portion 15 of the stem effects a cooling of the smoke in its passage therethrough. The stem of the pipe may readily be taken apart to allow for cleaning by removing the bypass 19 and unscrewing the respective sections.

20 From the foregoing description it will be clearly seen that by my invention there is provided a novel and very useful improvement in tobacco pipes and whilst I have 25 shown and described one practical embodiment thereof, the same is not to be too restrictively construed, as it will be obvious that various changes in the shape and disposition of the several parts may be effected 30 to adapt my said invention to different forms and styles of tobacco pipes; the right is therefore hereby reserved to make such reasonable changes and modifications as fairly lie within the scope of the appended claims.

Having described my invention, what I 35 claim as new and desire to secure by Letters Patent is:

1. A smoking pipe comprising a bowl having an integral stem, the outer end whereof is cup-shaped, a mouth-piece, the outer end whereof is correspondingly cup-shaped, means for connecting together said cup-shaped portions to complete the pipe as a unit, a partition in each of the aforesaid cup-shaped portions, the forward one of 40 which is provided with an aperture at its lower part and the rear one with an aperture at its upper part, and means for locking the aforesaid cup-shaped portions in operative connection.

2. A smoking pipe comprising a bowl having an integral stem, the outer end whereof is cup-shaped, a mouth-piece, the outer end whereof is correspondingly cup-shaped, means for connecting together said cup-shaped portions to complete the pipe as a unit, a partition in each of the aforesaid cup-shaped portions, the forward one of 45 which is provided with an aperture at its lower part and the rear one with an aperture at its upper part, and a by-pass connection on the upper part of the cup-shaped portion of the pipe stem which serves as a locking means for securing the opposed cup-shaped portions of the stem in operative connection.

50 In testimony whereof I affix my signature.
GEORGE SMITH.
